(57) CLAIM

The ornamental design for a mount for a license plate or similar article, as shown and described.

DESCRIPTION

FIG. 1 is a perspective view of a mount for a license plate or similar article according to the design;

FIG. 2 is a front view thereof;

FIG. 3 is a rear view thereof;

FIG. 4 is a right side view thereof, the left side view being a mirror image of the right side view; and,

FIG. 5 is a top view thereof, the bottom view being a mirror image of the top view.

1 Claim, 2 Drawing Sheets

FIG. 5
